(57) **CLAIM**

The ornamental design for a rotary hand pump drum connector, as shown and described.

DESCRIPTION

FIG. 1 is a perspective view of the rotary hand pump drum connector for a rotary hand pump shown in phantom.

FIG. 2 is a front elevation view of the rotary hand pump drum connector.

FIG. 3 is a first side elevation view of the rotary hand pump drum connector.

FIG. 4 is a second side elevation view of the rotary hand pump drum connector.

FIG. 5 is a rear elevation view of the rotary hand pump drum connector.

FIG. 6 is a bottom view of the rotary hand pump drum connector.

FIG. 7 is a top plan view of the rotary hand pump drum connector.

FIG. 8 is a perspective view of the rotary hand pump drum connector, with a rotary hand pump shown in phantom.

FIG. 9 is a front elevation view of the rotary hand pump drum connector.

FIG. 10 is a first side elevation view of the rotary hand pump drum connector.

FIG. 11 is a second side elevation view of the rotary hand pump drum connector.

FIG. 12 is a rear elevation view of the rotary hand pump drum connector.

FIG. 13 is a bottom view of the rotary hand pump drum connector; and,

FIG. 14 is a top plan view of the rotary hand pump drum connector.
